UNITED STATES PATENT OFFICE.

HOLMES MARSHALL, OF PLAINFIELD, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,196,257.

Specification of Letters Patent. Patented Aug. 29, 1916.

Application filed October 18, 1911. Serial No. 655,363.

To all whom it may concern:

Be it known that I, HOLMES MARSHALL, a citizen of the United States, residing in Plainfield, in the county of Union and State 5 of New Jersey, have invented certain new and useful Improvements in Combined Type-Writing and Computing Machines, of which the following is a specification.

This invention relates to a combined type- 10 writing and computing machine of the Underwood-Hanson type.

It has been found, in actuating a combined typewriting and computing machine, that some operators, through carelessness or for- 15 getfulness, after making an error while computing, will erase said error from the work sheet on the platen because it is so obvious and directly before their eyes, but will neglect to readjust the computing mechanism 20 so as to clear the error therefrom; the result being an inaccurate computation.

An object therefore of this invention is to prevent the turning back of the platen to 25 erase an error from the work sheet thereon until the error has been cleared from the computing mechanism by an actuation of the error key.

Inasmuch as when the end of a line is 30 reached, in a combined typewriting and computing operation, it is necessary to return the typewriter carriage, line-space the platen, and cause a complete cycle of the general operator of the computing mechanism, it is desirable to relieve the operator 35 of the labor and care incident to carrying out, individually, the several operations.

It is therefore a further object of this invention to utilize the actuation of the lever which concomitantly returns the carriage 40 and line-spaces the platen, to enable a complete cycle of the general operator of the computing mechanism by causing a connection thereto of motive means.

The machine with which this invention is 45 illustrated is of the Underwood-Hanson type, in which the numeral keys are connected, so that when they operate the type bars, they, individually, will also depress or set up each time a single pin, in a line of 50 pins located a certain distance from a given line, corresponding to the particular key

struck. The pins are supported in a series on bars, one for each numeral key on each bar. The bars are operated successively to correspond to the successive letter spaces 55 or denomination columns through the intermediary of a series of jacks operated successively by a tappet, or a series of tappets carried by the carriage, as the carriage moves step-by-step in a letter feeding di- 60 rection. The pins thus set up determine the extent of movement, of the bars on which they are located, caused by a general operator brought in action after the pin-setting operation has been completed. The 65 bars actuate a series of computing wheels amounts corresponding to their extent of movement. If an error occurs, the pins may be cleared, that is, brought back to their normal unset position, before the actuation 70 of the general operator to carry the set-up or indexed calculation to the computing wheels, by the depression of an error key.

To erase an error from the work sheet, the typist generally rotates the platen by 75 manipulating one of the knobs carried thereby, to bring the typewritten line on the work sheet up to a convenient position above the platen. In this invention, the knobs are connected to the platen so that they will 80 be incapable of rotating the platen in a line-spacing direction to bring the typewritten line up to an erasing position. Also in this embodiment of the invention the knobs are connectible to the platen by ball and cam- 85 cup clutches. The clutch for one of these knobs, in this case the left hand one looking at the machine from the front, is faced in such a direction that it may rotate the platen backward but not forward. The clutch for 90 the other knob, that is, the right hand knob, is faced in the opposite direction, so that by rotating this knob in a clockwise direction, it will rotate the platen forward. This latter knob, however, is locked against move- 95 ment normally by a pawl and ratchet wheel mechanism. The pawl and ratchet lock is releasable at the actuation of the error key through the intermediary of linkages, so that the right hand knob will be free to ro- 100 late the platen to raise the work sheet to an erasing position after the computing mecha-

nism has been cleared by the actuation of the error key.

In the particular type of the invention illustrated, it is found convenient to lock the error key in its actuated position, so that the typist can have both hands free to perform the erasure on the work sheet. It is evident that if the typist forgot to release the error key before continuing with the actuation of the machine to complete the computation, the accurate operation of the computing mechanism would be interfered with. There is therefore provided means for preventing the complete actuation of the keys, type bars and other connected mechanism while the error key is in its depressed or actuated position.

The general operator above mentioned is actuated by a motor normally disconnected therefrom, but connectible thereto by an automatic clutch, which in this case is brought in play through the intermediary of linkages, when the combined platen-spacing and carriage return lever is operated at the end of a line. In other words, when the carriage is returned for a new line, the computing mechanism will be given a complete cycle of movements by the concomitant connection of the general operator with the motor.

Other features and advantages will hereinafter appear.

In the accompanying drawings, Figure 1 is a part sectional side elevation of an Underwood-Hanson combined typewriting and adding machine embodying the present improvements. Fig. 2 is a sectional view of the clutch employed between the electric motor and the general operator of the adding machine. Fig. 3 is a fragmentary perspective view, showing the skeleton of the improved connection between the typewriting mechanism and the computing mechanism, whereby the one controls the other. Fig. 4 is a fragmentary section showing the detail of a guiding support for one of the links. Fig. 5 is a fragmentary top plan view of the mechanism shown in Fig. 3. Fig. 6 is a detached view in section, along two different lines, of the left hand end of the platen, and showing the connection of the knob thereto. Fig. 7 is a view similar to Fig. 6, of the right hand end of the platen. Fig. 8 is a vertical sectional view taken at right angles to the section shown in Fig. 6, and showing the same end of the platen with the connection of the knob to the platen. Fig. 9 is a vertical section similar to Fig. 8, of the right hand end of the platen, showing the parts illustrated in Fig. 7. Fig. 10 is a vertical section through one of the clutches for connecting one of the knobs to the platen.

A continuously running electric or other motor 1 is provided with a main shaft 2, the latter connected to a shaft 3 by means of a safety friction clutch, not shown. A rack

13, forming part of a rack frame or general operator, is movable forwardly and backwardly in the base of the adding machine, and performs the final portion of the computing operation. This rack frame is reciprocated intermittently by the constantly rotating shaft 3, by means of a clutch mechanism; said rack frame being connected to a crank shaft to be driven thereby, and the crank shaft being connected by a worm 75 gearing to said shaft 3, as will presently be set forth. Upon the rack frame is secured a yoke or carrier 14, in engagement with which is the upper end of an arm 15, provided on a cross head 16, which moves forwardly and backwardly, or from left to right at Fig 1, so as to reciprocate said rack frame 13; said cross head being carried on a horizontal slide 17, which works in bearings 18 on a casing 19. This slide is reciprocated by means of a crank 23, fixed on a horizontal shaft 24; said crank carrying a slide block 26, working in a groove 27 in the cross head. Loose on shaft 24 is a worm gear 30, meshing with a worm 31, the latter fixed on shaft 3, so that the worm wheel 30 is constantly rotating. The worm wheel 30 is connectible to shaft 24 to turn the same whenever it is necessary to reciprocate the rack frame 13 to complete a computing operation; and at the conclusion of said reciprocation, said worm wheel 30 is automatically disconnected from the shaft 24, and the latter comes to a stop, while the motor 1 continues to rotate.

Fixed to the shaft 24 is a cup member 32 of a clutch; and fixed to the hub of worm gear 30 is a collar 33. Running on this collar and adapted to engage the inside of a cylindrical face of the clutch cup 32, is a 105 gripping ball or roll 34; said roll occupying a pocket 35 in the clutch cup, and rolling on an inclined floor 35a thereof, so that relative movement of the clutch cup and collar 33 in one direction will cause said members 110 to be clutched together by the roll, while relative movement in the opposite direction will produce the opposite effect, so as to permit independent rotation of the gear 30.

The clutch roll is shiftable between gripping and releasing positions in the pocket 35 by means of an annular disk or ring 36, which rides loosely on the collar 33 within cup 32, and which is cut away at one place to receive the roll 34, so as to engage the roll on both sides thereof. Rotation of ring 36, therefore, shifts the roll. Against said ring 36 bears one end of a compression spring 38, which is confined within a pocket 37 formed in said ring; the other end of said spring bearing against a stop 39 secured to the inner side of the clutch cup. The pocket 37 is of sufficient length to permit a movement of the disk or ring 36 without interference from the stop 39. The

- spring tends to turn the ring 36 with the roll 34 in a direction to lock together the clutch cup with the bearing collar to cause shaft 24 to rotate with gear 30. In other words, said spring tends normally to close the clutch. Normally, however, said ring 36 is restrained from causing the roll to bind; or in other words, said ring is normally held in clutch-releasing position.
- For this purpose, there is provided a trip pin or latch 40, normally in engagement with a lug 41 provided upon releasing ring 36, said lug projecting through an opening in the clutch cup. When shaft 24 is to be clutched to the gear 30, the latch 40 is raised to release lug 41, whereupon spring 38 throws ring 36, together with roll 34, thus locking the clutch cup and the shaft 24 to the rotating worm gear 30. The pin 40 is automatically dropped again into the path of lug 41, so that at the completion of a single rotation of the shaft 24, the latter is again unclutched from the worm gear 30. The rack frame 13 is caused to reciprocate after the numeral keys of the typewriter have been operated to set up a number. This rack frame operates to turn the computing wheels to different extents, depending upon the key operated.
- I will first describe means whereby the typist may depress a special key to operate said clutch, and cause the reciprocation of the rack frame or general operator. Said key is designated as 42, and is mounted on a stem 43, pivoted at its lower end to a lever 44, fulcrumed at 45 upon the machine frame. Said lever 44, in turn, depresses a cross lever 46, which is pivoted at 47 to the framework, and at its other end engages a notch 48 formed in the top of the trip pin or latch 40, so as to cause or control the up and down movement of said latch, whereby the clutch is caused to close and open. The lever 46 is provided with an adjustable end or arm 50, upon which the key lever 42 bears; this part 50 being adjustable by screws 52, thereby securing accuracy of adjustment and movement of the clutch-controlling mechanism. Depression of the key 42 carries down the lever 44, the latter rocks the lever 46 about its fulcrum 45, the other end of the lever 46 lifting the latch 40 away from the clutch lever 41. The typist immediately releases the key 42, which is returned to normal position by a spring 54. The movement of the key is limited by a pin 55 within a slot 56 in the key stem. The lever 46 has a returning spring 57.
- The typewriter includes the usual set of type-operating keys, including alphabet keys and also including numeral keys 88 mounted on levers 88^a and connected by bell cranks 89 to type bars 90, which are thrown back against a platen 91 mounted on a carriage 92. The carriage is power-driven, as usual, and has a rack 87 meshing with a pinion 86, connected with an escapement wheel 85, the latter controlled by dogs 84, operated by a universal bar 83, which is actuated by the type bars, so that whenever any type key is actuated, the carriage 92 is caused to feed a letter space.
- The universal bar 83 and the mechanism operated thereby may be termed the "escapement mechanism", in that it permits the escapement of the carriage, and may be indicated generally by the reference numeral 85^a. This escapement mechanism is utilized, as will be described hereinafter, to prevent the operation of the typewriter when certain elements of the computing mechanism are not in their proper position to be operated.
- Fastened at the back of the carriage 92, are brackets 93, carrying a rack 94, to receive adjustable cams or tappets 95. Whenever any tappet, during the travel of the carriage, passes beneath the set of jacks 96, it raises the forward ends of the jacks in succession, turning each on its pivot 97, and depressing its rear end to press down the corresponding one of a set of wires 98. These wires are connected at their lower ends to levers 99 on a fulcrum rod 100. Each lever 99 raises one of a set of linkages 101; each linkage having a pin 102 to lift the rear end of a rack bar 103, the forward end of which meshes with a pinion 104 connected to a computing wheel 105. Each rack bar carries a set of pins 106, and one of these is depressed by the operated type key 88; each key having a stem 110, for this purpose, to depress a crank 112, fast to a shaft 113, which is connected to a linkage 114, to depress one of the pins 106 upon the lifted rack bar 103; there being one linkage 114 for each key, each linkage being in position to depress a corresponding pin 106 on whichever rack bar is lifted. After the keys 88 are manipulated to write a number, and the corresponding racks 103 accordingly elevated as the paper-carriage feeds along, and certain pins 106 thereon depressed, there must be caused a reciprocation of the rack frame or general operator 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935

are temporarily set up, and from which the numbers are carried into the computing wheels 105.

If an error is made, the operator may 5 press an error key 120, the stem of which has an arm 121 to which is attached one end of a draw spring 122, the upper end of said spring being connected to a lever 123 having a projection 124 to rest on the top of a trip 10 125. A wrist 126 on the descending stem 121 presses said trip aside and allows the spring 122, which has been accumulating power, to pull down said lever with a snap. The rear end of the lever rises and engages 15 a wrist 127 on one of a pair of bell cranks 128, and thereby lifts a universal pin-restoring plate or tablet 129 to return to normal positions any of the pins 106 that may have been set. When the error key is released, a 20 spring 130 returns it to normal position.

As has been stated above, it is desirable to prevent the operation of the platen 91 until the error key 120 has been actuated to clear the error from the computing mechanism 25 by unsetting the pins 106. To this end, the platen is made somewhat different from the ordinary Underwood platen, and, as will be seen by reference to Figs. 6 to 10, includes a shaft 131 to which the platen roller 132 is secured, and which is provided at its left and right ends with hubs or collars 133 and 134 secured thereto, so as to move therewith, in any suitable manner, as by means of set screws 135. In this instance, the platen is 30 provided with knobs 136, 137 for the purpose of rotating the platen, but these knobs are not rigidly connected to the platen. That is to say, the knobs which form an actuating means for rotating the platen are connectible at times through the intermediary of clutches 138 and 139 to the platen, so as to rotate the same. The clutch illustrated in this case is of the ball and cam-cup type, as will be seen more clearly by reference to 40 Figs. 6 to 10. The hubs 133 and 134 are each provided with a cylindrical socket or cavity 140, in which extends an enlargement 141 provided on each of the knobs. Each of these enlargements is provided with a 45 pocket or cup 142, which is deepest at one end and gradually tapers to the surface of the enlargement, so as to form a spiral cam on which a ball 143 may roll. This ball 143, in each case, is urged away from the deepest portion of the cam by means of a spring 144, which, however, will yield when sufficient force is applied to permit the ball to recede in the deepest portion of the cam cup, out of clutching connection with the 50 inner surface of the hubs 133 and 134. The knobs 136 and 137 are otherwise loosely connected to the hubs 133 and 134, and thus to the platen by means of screw shafts 145. The only difference between the clutches 55 138 and 139 is that they are faced in oppo-

site directions, so that they are capable of rotating the platen in opposite directions, but are incapable of rotating the platen in the other directions. That is to say, if the operator faces the machine and rotates the 70 left knob 136 up over toward himself, the ball will roll on the inclined surface at the bottom of the cam cup and be clutched between this surface and the inner surface of the hub 133, so that it will be connected to 75 the platen to rotate it in a counter-direction to that of normal line-spacing. If, however, this knob 136 is rotated up over to the rear, the ball 143 will sink against the tension of the spring 144 into the deepest 80 part of the pocket 142, thus forming no connection between the knob and the platen. On the other hand, if the right hand knob 137 is rotated up over toward the rear, the knob 137 will be positively connected by the 85 clutch 139, so as to tend to rotate the platen in a line-spacing direction, but a rotation of the knob 137 in the opposite direction would permit it merely to run freely without operating the platen. The rotation of the platen 90 91 by the right hand knob 137 in a line-spacing direction is, however, prevented by a pawl 146, which engages a ratchet wheel 147 and prevents the rotation of the knob 137 on which the ratchet wheel is secured, 95 thus forming a locking means preventing the actuation of the platen through the intermediary of the knob 137 for the purpose of correcting an error. It will thus be seen that the typist cannot rotate the platen by 100 actuating either of the knobs 136 or 137 in a manner to bring the work sheet up above the platen for the purpose of erasing an error just committed, until the lock embodying the pawl 146 and the ratchet wheel is released. The release of this lock is accomplished when the error key 120 is depressed to clear the computing mechanism of the error. For this purpose, there is loosely 105 mounted on the hub 133 and the knob 137, 110 a bail 148, which is provided with a tripping pin 149 located on one of the arms of the bail, so as to remove the pawl 146 from engagement with the ratchet wheel 147.

The bail 148 may be operated by a link 115 150, which is connected at its lower end to a bell crank lever 151, the farther arm of which is connected by a link 152 to a bell crank lever 153 having one arm underlying the end of the stem of the error key 120. This last bell crank lever 153 may be returned to its normal position by means of a spring 154. The extent of movement of the bail 148 and the linkages connected thereto may be controlled by a pin 155, which, as will be seen by reference to Fig. 4, is secured to a suitable portion of the frame and engages a slot 156 of predetermined magnitude provided in the link 150.

Inasmuch as it is desired to relieve the 130

operator of the necessity of holding the error key 120 depressed, while adjusting the platen and while erasing the error on the work sheet on the platen, there is provided 5 a lock for the error key, which in this instance is shown to embody a latch 157 adapted to engage a notch 158 formed in a catch 159 provided on the stem of the error key 120. This latch can be readily released by 10 swinging it about its pivot. It might sometimes happen that the typist, after correcting the error on the work sheet, would return the work sheet to its original position and start a further computation, without 15 thinking to release the lock for the error key, and thus have an inaccurate operation of the machine. To avoid this, the link 150 is provided with an obstructing member or stop 160, which, while normally located in 20 an unobstructing position, is depressed, with the actuation of the error key, to such a position that it will interfere with the operation of the escapement mechanism 85^a, and thus by virtue of the universal bar 83 forming 25 a part of the escapement mechanism lying in the path of the type bars 90, will prevent the complete throw of said type bars, and thus lock the keys 88 against complete movement. As soon as the error key 30 120 is permitted to return to its normal position, the stop 160 will be raised out of alignment with the escapement mechanism permitting the carriage, the type keys and the mechanism connected thereto to be once 35 more brought into operation.

I have thus far shown how a certain portion of the typewriting mechanism, to wit: the platen, is controlled in its operation from a certain portion of the computing mechanism, to wit: the error key. It now remains 40 to show how the actuation of the platen, and the carriage on which the platen is located, controls the operation of the computing mechanism by enabling the normally disconnected motor to be connected to the general operator of the computing mechanism by the automatic clutch. This is accomplished by lifting the latch 40 away 45 from the clutch lug 41 by means, other than the key 42, which is controlled from the typewriting mechanism. If we refer once more to Figs. 6 and 8 and also to Fig. 1, it 50 will be seen that the hub 133, which is secured to the shaft 131, and thus to the platen 91, is provided with a line-space ratchet wheel 161 of the usual Underwood type, which is engaged by a spring-pressed pawl 162 on a slide bar 163. This slide bar is normally held by a spring 164 in such a position 55 that it can be forced rearwardly by means of the usual line-space lever 165, which is pivotally mounted on the carriage 92 in such a manner that it can be used not only to rotate the platen 91, but also to return the carriage 60 to its starting point after a movement 65 in a letter feeding direction. The slide bar 163 is provided with a pair of pins 165 and 166, which are adapted to oscillate a bell crank lever 167 having one of its arms projecting between them. The other arm of the bell crank lever 167 engages an arm 168 forming a part of a bell crank lever 169, the other arm of which is formed by a bail 170. The bail, when depressed by the rearward movement of the slide bar 163, will engage 70 the turned over flange 171 on a link 172, and thus rock a lever 173 connected by a link 174 to a bell crank lever 175, which rests on the latch lever 46 on the opposite side of its fulcrum from the latch 40, so that when the 75 line-space lever 165, is operated, it will at the same time remove the latch pin 40 from the path of the clutch lug 41, permitting the clutch to operatively connect the motor in driving relation with the general operator. 80 The link 172 may be guided and limited in its motion by a pin 176 engaging a slot 177 provided therein. This mechanism may be returned to its normal position by means of a spring 178, which is shown as connected to 85 the bell crank lever 175.

In the operation of the device, the typist strikes the keys 88 so as to concomitantly print the numerals to be computed on the work sheet on the platen 91, and at the same 90 time set up the pins 106, so as to index the numbers, for the purpose of subsequently carrying them to the computing wheels 105. We will assume that the typist has made an error and desires to correct the same. It will 95 be seen that if the typist endeavors to rotate the platen 91 so as to bring the work sheet to a position such that the error will lie above the platen where it can be conveniently erased, by rotating the left knob 100 136, this knob will rotate freely without turning the platen in the direction desired. It will be further seen that it is impossible to rotate the other knob 137, inasmuch as this knob is locked by the pawl 146. It is 105 therefore necessary that the typist must first clear the computing mechanism of the error by depressing the error key 120. A depression of the error key 120 will raise the clearing plate so as to unset the pins 106, returning 110 them to their normal positions. When the error key 120 is depressed, it will be automatically locked in its depressed position by the latch pawl 157, so that the operator will have both hands free to turn the 115 platen 91 up to the desired position by rotating the right hand knob 137, which has in the meantime been released by the pin 149, tripping the pawl 146 when the error key 120 was depressed to clear the computing 120 mechanism of the error. While the platen cannot be turned back to bring the work sheet to the proper position to receive the correction by turning the right hand knob 137, it can be brought back by turning the 125 130

left knob 136, which will be connected to the platen when rotated in an over and forward direction by its clutch 138. If the typist should endeavor to actuate the machine by striking the keys 88 before releasing the error key 120, it will be seen that the stop 160 will prevent the complete movement of the escapement mechanism 85^a, and thus prevent not only the travel of the carriage 92, but also the complete actuation of the type bars 90 and the keys 88, thereby warning the typist that the error key 120 has not been released. After releasing the error key, the operator then continues the combined typewriting and computing until the end of a line is reached, when the combined line-spacing and carriage return lever 165 is actuated so as to concomitantly rotate the platen to bring the work sheet up to a new line, and at the same time return the carriage to its starting point at the right. This movement of the lever 165 will, at the same time, through the connecting linkages, remove the latch pin 40 from the path of the clutch lug 41, permitting the automatic clutch to shift itself to such a position that it will operatively connect the worm wheel 30, and thus the motor 1 in driving relation with the general operator, so as to obtain a concomitant cycle of movements of the computing mechanism.

Variations may be resorted to within the scope of the invention, and portions of the improvements may be used without others.

Having thus described my invention, I claim:

1. The combination with a typewriting mechanism including a platen, of computing mechanism including an error key for clearing the computing mechanism of an erroneous portion of a calculation, and means brought in play by said error key for enabling the actuation of said platen.

2. The combination with a typewriting mechanism including a platen, of computing mechanism including an error key for clearing the computing mechanism of an erroneous portion of a calculation, and connections between said platen and said error key for controlling certain operations of the one from the other.

3. The combination with a typewriting mechanism including a platen, of computing mechanism including an error key for clearing the computing mechanism of an erroneous portion of a calculation, a lock connected to said platen, and connections between said error key and said lock, whereby said lock may be released by an actuation of said error key, to enable the actuation of said platen.

4. The combination with a typewriting mechanism including a platen, of computing mechanism including an error key for clearing the computing mechanism of an erroneous portion of a calculation, a lock connected to said platen, and connections between said error key and said lock, whereby said lock may be released by an actuation of said error key, to enable the actuation of said platen.

ous portion of a calculation, means brought in play by said error key for enabling the actuation of said platen, and a lock for holding said error key in its actuated position.

5. The combination with a platen, of actuating means for said platen, a lock for preventing operation of said actuating means, computing mechanism including a special key, and connections between said key and said lock, whereby said key may release said lock concomitantly with the performance of its special operation, to enable the operation of said platen by said actuating means.

6. The combination with a platen, of means for rotating said platen, a clutch for connecting said means to said platen, and a lock for preventing the operation of said platen by said means.

7. The combination with a platen, of means for rotating said platen, a clutch for connecting said means to said platen, a lock for preventing the operation of said platen by said means, and a key for releasing said lock.

8. The combination with a platen, of means for rotating said platen, a clutch for connecting said means to said platen, a lock for preventing the operation of said platen by said means, computing mechanism including a key for operating certain parts of said computing mechanism, and connections between said lock and said key, whereby said key may control said lock as well as said certain parts of said computing mechanism.

9. The combination with a platen, of means for rotating said platen, a clutch for connecting said means to said platen, a lock for preventing the operation of said platen by said means, computing mechanism including a key for operating certain parts of said computing mechanism, connections between said lock and said key, whereby said key may control said lock as well as said certain parts of said computing mechanism, and a lock for said key.

10. The combination with typewriting mechanism including a platen, a knob for rotating said platen, a one-way clutch for connecting said knob to said platen, and a lock for preventing the rotation of said platen by said knob, of computing mechanism including a key for manipulating certain parts of said computing mechanism, and connections between said key and said lock, whereby said key can release said lock to permit the rotation of said platen by said knob.

11. The combination with a typewriting mechanism including a platen, a knob for said platen, a ball and cup clutch connecting said knob to said platen, so that said knob will be capable of rotating said platen solely in one direction, a second knob for said platen, a clutch for said second knob, and a

- lock for preventing the rotation of said second knob, of computing mechanism including a key for operating certain parts of said computing mechanism, and connections between said key and said lock, whereby 5 said lock may be released by said key, to permit the rotation of said platen by said second knob.
12. The combination with a typewriting 10 mechanism including a platen, a knob, a clutch for connecting said knob to said platen, so that said clutch can rotate said platen solely in one direction, a second knob, a second clutch for connecting said second 15 knob to said platen so that said second knob can rotate said platen solely in the opposite direction to that in which said first mentioned knob can rotate said platen, and a lock for preventing the rotation of said 20 platen by one of said knobs, of computing mechanism including a key for operating certain parts of said computing mechanism, and connections between said key and said lock, whereby said lock may be released concomitantly with the actuation of said certain parts of said computing mechanism by 25 said key.
13. In a combined typewriting and computing machine the combination with typewriting mechanism including a platen and means for rotating said platen, of computing mechanism, operating means for said computing mechanism, and connections between said platen-rotating means and said 30 operating means, whereby said platen-rotating means may control the actuation of said operating means.
14. The combination with a typewriting 35 mechanism including a platen, and means for rotating said platen, of computing mechanism including a general operator for said computing mechanism, a motor normally disconnected from said operator, and means governed by said first-mentioned traversing 40 means for controlling the operative connection of said general operator with said motor.
15. The combination with a typewriting 45 mechanism including a carriage, of means for line spacing and traversing said carriage, computing mechanism including a general operator for obtaining a cycle of operations of said computing mechanism, and connections between said line spacing and traversing means and said computing mechanism, whereby the actuation of the former to traverse said carriage will cause a concomitant actuation of the latter.
16. The combination with a typewriting 50 mechanism including a platen and means for rotating said platen, of computing mechanism including a general operator for said computing mechanism, a motor normally disconnected from said operator, mechanism 55 for connecting said general operator with said motor, and means controlled by said platen-rotating means enabling the concomitant effective connection of said general operator to said motor with a rotation of said platen.
17. The combination with a carriage, of means for line spacing and returning said carriage, computing mechanism including a general operator for giving a complete cycle of movements thereof, a motor normally disconnected from said operator, mechanism for connecting said general operator with said motor, and means controlled by said line spacing and carriage returning means enabling the concomitant effective connection of said general operator to said motor with the return of said carriage.
18. The combination with typewriting mechanism including a carriage, escapement mechanism for said carriage, and a platen on said carriage, of computing mechanism including a special key, means enabling the control of said platen by said key, and a stop operated by said means for preventing the actuation of said escapement mechanism while said key is in its actuated position.
19. The combination with a typewriter platen, of computing mechanism including an error key for clearing the computing mechanism of an erroneous computation, and means for preventing erasure of an error on a work sheet on said platen until said error key has been actuated to clear the error from said computing mechanism.
20. The combination with a typewriter 100 platen, of typewriting mechanism coöperating with said platen to write on a work sheet on said platen, means for preventing the erasure of an error from the work sheet on said platen, computing mechanism including an error key for clearing an erroneous computation from said computing mechanism, and connections between said error key and said first-mentioned means, whereby the operation of correcting an error on said 105 work sheet can be controlled from said error key.
21. The combination with a typewriter platen, of typewriting mechanism coöperating with said platen to write on a work sheet on said platen, means for preventing the erasure of an error from the work sheet on said platen, computing mechanism including an error key for clearing an erroneous computation from said computing mechanism, connections between said error key and said first-mentioned means, whereby the operation of correcting an error on said 110 work sheet can be controlled from said error key.
22. The combination with a typewriter platen, of typewriting mechanism coöperating with said platen to write on a work sheet 115

- on said platen, means for preventing the erasure of an error from the work sheet on said platen, computing mechanism including an error key for clearing an erroneous computation from said computing mechanism, connections between said error key and said first-mentioned means, whereby the operation of correcting an error on said work sheet can be controlled from said error key, 5
- 10 a stop for preventing the actuation of said typewriting mechanism while said error key is in its actuated position, and a latch for securing said error key in its actuated position.
- 15 23. The combination with a typewriting mechanism for inscribing on a work-sheet the numbers of a computation, of a computing mechanism including means for setting up the computation, and coöperating 20 means for preventing for one of said mechanisms the correction of an error without a corresponding correction for the other of said mechanisms.
24. The combination with a typewriting mechanism for inscribing on a work-sheet the numbers of a computation, of a computing mechanism including means for setting up the computation, and coöperating means for preventing the correction of an 25 error on said work-sheet without a corresponding correction of the numbers set up by said computing mechanism.
25. In a computing machine, the combination with a computing mechanism, of an error-correcting mechanism for said computing mechanism, numeral keys, a device common to all of said keys to be operated thereby, and a stop movable by said error-correcting mechanism into the path of the 30 key-operated device for preventing the actuation of said numeral keys while said error-correcting mechanism is in play.
26. In a combined typewriting and computing machine, the combination with a typewriting mechanism, including a platen and a line-space lever, of a computing mechanism, and controlling means for governing the action of said computing mechanism from said line-space lever.
- 45 27. The combination with a typewriting mechanism, including a platen and a line-space mechanism for said platen, of a computing mechanism, including means for indexing a computation of numbers written by said typewriting mechanism and a general operator for running up said indexed computation, and a line-space mechanism controlled means for enabling the actuation of said general operator concomitantly with 50 the line spacing of said platen.
- 55 28. The combination with a typewriting mechanism including a platen and a line-space mechanism for said platen, of a computing mechanism, operating means for said computing mechanism, and a line-space 60
- 65 mechanism controlled means for controlling the action of said operating means.
29. The combination with a typewriting mechanism having a carriage, of a computing mechanism having computation indexing means, registering means and a general operator for causing the transfer of the indexed computation to the registering means, a manually-operable member on said carriage enabling the return of said carriage, 70 and means operated by said member for enabling the actuation of said general operator. 75
30. The combination with a typewriting mechanism having a carriage with a platen, of a computing mechanism having a general operator, and means operable from a single point other than at the general operator and distant therefrom, for concomitantly causing a spacing of the platen, the 80 return of the carriage to variable extents and from any point in a line and the complete actuation of the general operator.
31. The combination with a typewriting mechanism including a platen, platen-space mechanism and a lever for operating said platen-space mechanism, of computing mechanism including a general operator and means for subjecting the control of the movement of said general operator to said 85 lever.
32. The combination of a typewriting mechanism including a platen, line-space means for said platen, a computing mechanism having a general operator, and means 90 operated by said line-space means for causing the actuating of said general operator.
33. The combination of a typewriting mechanism having a carriage, means to line space and return said carriage, a computing mechanism having a general operator, and single-acting mechanism operated by said means at each actuation thereof, to produce a complete cycle of movement of said general operator. 95
34. The combination with a typewriting mechanism including a traveling carriage and line-space means on said carriage, of a computing mechanism including a general operator, means enabling the actuation of 100 said general operator, and connections operable by said line-space means at any point in the movement of said carriage for actuating said last-mentioned means to enable the actuation of said general operator. 110
35. The combination with a carriage, of a platen on said carriage, line-space mechanism for said platen, a computing mechanism including a general operator, a source of power, an automatic controller tending to 115 connect said general operator to said source of power, a disconnector for said automatic controller, and line-space mechanism operated means for moving said disconnector to its ineffective position. 120
- 125

36. In a combined typewriting and computing machine, the combination with a rotatable platen, of means for rotating it in one direction only to thereby position a work-sheet where an error thereon may be corrected, a pawl normally effective to prevent operation of such means, releasing means for said pawl, and a latch for holding said pawl in released position. 5
- 10 37. In a typewriting machine, the combination with a revoluble platen, of a normally inoperable manual device whereby the platen may be rotated in the operation of correcting an error, computing mechanism including a set of key-controlled indexing devices, means including an error key for restoring said indexing devices to enable an error to be corrected, and means set by said error key to permit the rotation 15 of the platen by said manual device. 20
38. The combination with a typewriting mechanism including a platen, and means for rotating the same, of computing mechanism including a general operator, a motor normally ineffective to drive said general operator, and automatic means controlled from said platen-rotating means for causing the concomitant driving of said general operator by said motor with a rotation of said platen. 25
39. In a combined typewriting and computing machine, the combination, with a traveling carriage, and an escapement for controlling the travel of said carriage including a universal bar; of devices for temporarily indexing or setting up the numbers to be computed; numeral keys for setting said indexing devices, said keys also arranged to coöperate with said universal bar in actuating said escapement; universal 40 restoring means for the set indexing devices; and a member connected to be moved by said restoring means into the path of said universal bar, so as to obstruct the operation of said keys while said restoring 45 means is in action. 5
40. The combination with a typewriting mechanism including a carriage, a platen, and a line-space mechanism for said platen, of a trip located in the path of a certain moving part of said line-space mechanism, a computing mechanism including a general operator, enabling means causing the actuation of said general operator, and universal connections between said trip and said enabling means, whereby the movement of said trip can be caused to bring about the actuation of said enabling means at any point in the movement of said carriage. 50
41. The combination with a typewriting mechanism, including a platen, a traveling carriage, and a line-space lever for said carriage, of a computing mechanism, including a general operator and means for actuating said general operator, and a one-way effective connection lying in the path of said line-space lever acting to control the drive of said general operator by said actuating means. 60
- 65
